Patented Sept. 1, 1914.

UNITED STATES PATENT OFFICE.

FRED K. LEWIS, OF ASHTABULA, OHIO, ASSIGNOR TO THE ASHTABULA BOW SOCKET COMPANY, OF ASHTABULA, OHIO, A CORPORATION OF OHIO.

VEHICLE TOP-SUPPORT.

1,109,431.

Specification of Letters Patent.

Patented Sept. 1, 1914.

Application filed April 6, 1912. Serial No. 688,824.

To all whom it may concern:

Be it known that I, FRED K. LEWIS, a citizen of the United States, and a resident of Ashtabula, county of Ashtabula, and 5 State of Ohio, have invented a new and useful Improvement in Vehicle Top-Supports, of which the following is a specification, the principle of the invention being herein explained and the best mode in which 10 I have contemplated applying that principle, so as to distinguish it from other inventions.

The present invention relates to supporting means for vehicle tops of the canopy or 15 cape type, which may be held in a raised or a lowered position. It is usual in this type of tops to provide main supporting members and auxiliary supporting members, which may be disconnected from the main supports 20 when the top is folded in its lower position in order to provide a snug and close fitting construction.

It is a simple matter to construct an efficiently operating and compactly folding 25 top when the supporting members are all straight, but in the flared tops now in such general use, it is necessary to provide a construction which will permit of compact folding of the main and auxiliary supports 30 which, in many cases, are both of curved construction.

To the accomplishment of these and related ends, said invention, then, consists of the means hereinafter fully described and 35 particularly pointed out in the claims.

The annexed drawing and the following description set forth in detail certain mechanism embodying the invention, such disclosed means constituting, however, but one 40 of the various mechanical forms in which the principle of the invention may be used.

In said annexed drawing:—Figure 1 is a front view showing the main and auxiliary supporting members in their positions when 45 the top is raised; Fig. 2 is a similar view showing the position of these two members when the top is folded; Fig. 3 is a side elevation of the arrangement shown in Fig. 1, and Fig. 4 is a side elevation of the arrangement shown in Fig. 2.

In Fig. 1 there is a main supporting member 1 which will be straight for a greater portion of its length, but will be curved at its lower end and will have attached to it 55 an auxiliary supporting member 2, which

will conform in shape to the main member, being straight for the greater portion of its length and curved at its lower end. The means of attachment of the auxiliary member to the main supporting member comprise a socket 3 mounted at the lower end of the main member, and a second socket 4 offset from the main member at a point intermediate of the ends of the same. At the lower end of the auxiliary member there is 60 mounted a pin 5 which is adapted to detachably engage either of these two sockets and to be held in such engagement by means of a cotter pin 6.

By offsetting the upper socket 4, it is 70 possible to permit the main and auxiliary supports to lie in substantially the same plane when the top is in its raised position, the only portion of the auxiliary member which is not in such a plane being the 75 lower end, which is, of course, in a plane parallel to, but spaced from, the imaginary plane already mentioned. When the members are engaged in the lower position of the top, it will be seen from Fig. 2 that 80 the auxiliary and main supporting members will not only be in the same plane throughout their length, but will be parallel to each other, the curved portion of the auxiliary member conforming substantially to the 85 curved portion of the main member.

The advantages of such a construction are several. The bows of the top are very 90 much more slight in appearance, and when used with curved supporting members and in the folded position, a compactness is secured which is not possible with any other construction.

Other modes of applying the principle of my invention may be employed instead of 95 the one explained, change being made as regards the mechanism herein disclosed, provided the means stated by the following claim or the equivalent of such stated means be employed.

I therefore particularly point out and distinctly claim as my invention:—

In a vehicle top support, the combination of a main supporting member curved at its lower end, said member having an engaging member mounted intermediate its ends and extending laterally therefrom and a similar engaging member mounted at the lower end of said supporting member, and an auxiliary supporting member having a 100 105 110

similar curved portion adjacent one end, such end being adapted to engage either such offset, laterally engaging member, or such member at the end of said main member, whereby, in the first-named position, said main and auxiliary supporting members will lie parallel to each other through their straight portions, and in the second position, said members will lie substantially

in contact throughout their length, thereby facilitating their interconnection and the attachment of a cover for said vehicle top.

Signed by me this 3 day of April, 1912.

FRED K. LEWIS.
